UNITED STATES PATENT OFFICE.

HERMAN HERSCHEL, OF JERSEY CITY, NEW JERSEY.

NOODLE-MACHINE.

No. 828,207.

Specification of Letters Patent.

Patented Aug. 7, 1906.

Application filed December 31, 1904. Serial No. 239,119.

To all whom it may concern:

Be it known that I, HERMAN HERSCHEL, a citizen of the United States, residing at Jersey City, in the county of Hudson and State of New Jersey, have invented new and useful Improvements in Noodle-Machines, of which the following is a specification.

My invention relates to machines for manufacturing noodles and the like, and its primary object is to provide a new and useful device of this character which is cheap of construction, easily manufactured, durable, and efficient.

The invention consists in the construction, combination, and arrangement of parts, hereinafter fully described, claimed, and illustrated in the accompanying drawings, wherein—

Figure 1 is a perspective view of a machine constructed in accordance with my invention. Fig. 2 is a central vertical sectional view thereof. Fig. 3 is a side elevation of the machine, the plunger or follower and the mechanism for operating the same being swung to one side to clear the cylinder. Fig. 4 is a sectional view on the line 4 4, Fig. 2. Fig. 5 is a similar view on the line 5 5, Fig. 2; and Fig. 6 is a detail sectional view of the cylinder.

Referring to the drawings by reference-numerals, 1 designates an annular base provided with a central opening adapted to receive the lower end of the cylinder 2, and at quarterly intervals around said opening and adjacent thereto are apertures for the reception of the lower ends of rods 3 of the support 5, said rods 3 having their ends reduced and threaded, the lower of which are held in position by nuts 7 on the under side of the base-plate 1, while the upper ends are fastened to the support 5 by screwing therein.

The support 5 is provided with a central opening similar to and alining with the opening in the base-plate 1, adapted to receive the upper end of the cylinder 2, and said support 5 has its inner edge countersunk to provide a shoulder 7', which serves as the hanging medium for the cylinder 2 by the flange 8. The cylinder 2 has its lower end provided with an inwardly-directed flange 9, designed to loosely support a perforated disk 10. Thus it may be readily removed therefrom and permit the substitution of a disk having larger or smaller perforations. The support 5 is provided with ears 11 and 12, the former of which acts as a hinge for the member 15 of

the press-frame, while the ear 12 is the locking means for the press-frame, for which purpose a lock-pin 17 is provided.

The press-frame comprises two parallel cross-bars 14 and 14' of unequal length, the upper being the shorter, connected by two bars 13, angularly disposed and terminating in the hinging means and locking means of the press-frame in the manner above described.

Each of the cross-bars 14 and 14' is provided with two smooth-bore and one thread-bore recess, the latter being positioned midway between the former or centrally disposed with relation to the cylinder.

The press-frame is adapted to support a plunger or follower and the means for operating the same in such manner that the plunger or follower may be moved vertically within the cylinder 2, and be swung to one side to clear the cylinder. Rods 18 are slidably mounted within the smooth-bore recesses and have secured to their lower ends a follower or plunger 19, and rigidly secured to their upper ends is a plate 20. A screw-rod 21, located between and parallel with the rods 18, is the pressing means for the plunger to which it is swiveled in order to permit the screw-rod 21 to be revolved to reciprocate the plunger or follower within the cylinder 2. The upper end of the screw-rod 21 projects above the plate 20 and has secured thereto one end of a crank-handle 22, by means of which the screw-rod 21 may be revolved.

The manner of operation of the device may be stated as follows: The machine is first placed in position over a receptacle of water and then the press-frame is swung into the position shown in Fig. 3 to remove the plunger or follower 19 from the cylinder 2. In this position of the plunger the cylinder 2 may be supplied with the desired mixture and then the press-frame is swung into the position shown in Figs. 1 and 2 to position the plunger or follower within the cylinder, the frame being held in this position by means of the pin 17. By turning the crank-handle 22 the mixture within the cylinder is forced out through the apertures in the disk 10 into the water in the receptacle. This operation is continued until the mixture within the cylinder has been exhausted, and then the cylinder may be again supplied in the manner described. The size of the noodles may be regulated by substituting for the disk 10 a disk having larger or smaller perforations.

Having thus described the invention, what I claim is—

- In a noodle-machine, the combination of an annular base provided with a central opening, parallel rods rising vertically from said base and removably secured thereto, a support removably secured to the upper ends of said rods and provided with a central opening and having a shoulder countersunk 5 therein, said support having alining ears, a cylinder having an upper outwardly-turned flange and a lower inwardly-turned flange, said upper flange adapted to hang from the shoulder of the support, and said lower flange adapted to hold a disk, a plunger movably mounted within the cylinder, a press-frame comprising two angular and two par-

allel disposed bars designed to hinge to one ear and be locked by the other ear, guide and supporting rods slidably mounted on the press-frame and having their lower ends connected to the plunger, a plate secured to the upper ends of the guide-rods, a screw-rod disposed between said guide-rods and engaging with the press-frame and swiveled to 20 the plate and plunger, and a crank-handle secured to said screw-rod.

In testimony whereof I affix my signature in presence of two witnesses.

HERMAN HERSCHEL.
